UNITED STATES PATENT OFFICE.

CARL B. CHEEK, OF ENTERPRISE, IOWA.

LIFE-SAVING SUIT.

1,221,417.

Specification of Letters Patent.

Patented Apr. 3, 1917.

Application filed December 28, 1915. Serial No. 69,090.

To all whom it may concern:

Be it known that I, CARL B. CHEEK, a citizen of the United States, residing at Enterprise, in the county of Polk and State of Iowa, have invented certain new and useful Improvements in Life-Saving Suits, of which the following is a specification.

This invention has relation to certain new and useful improvements in life saving suits, and has for its primary object the provision of a suit which will be constructed in such manner and formed of such material as to be water proof and enable the party wearing the same to float in water an unlimited number of hours.

The invention has for another object the provision of a suit of this character which will be of such construction that it may be readily secured in position and fastened upon a party before entering the water, the suit being protected at its seams to prevent entrance of the water.

The invention has for another object the provision of a suit of this character which will be of such construction that it may be readily adjusted and securely fastened around the neck and limbs of the wearer.

The invention has for a further object the provision of a suit of this character including inflated members at predetermined portions of the suit, and means for supporting a life belt around the waist of the wearer.

With the above and other objects in view, the invention resides in the novel construction, combination, and arrangement of parts as hereinafter set forth in the specification, pointed out in the claims, and shown in the drawings, in which—

Figure 1 is an elevation of the complete suit with the outer section of the front partially closed;

Fig. 2 is a transverse section substantially on the plane of line 2—2 of Fig. 1;

Fig. 3 is a transverse section substantially on the plane of line 3—3 of Fig. 1; and

Fig. 4 is a fragmentary detail view showing the lower portion of the tongue for the front of the suit.

Fig. 5 is a cross sectional view on the line 5—5 of one of the leg portions of the improved suit.

Referring more particularly to the drawings in which similar reference characters designate corresponding parts throughout the several views, 1 designates the body of the suit having sleeves 2 projecting from its

shoulder portions 3 and provided with integral gloves 4 at their outer end. The body 1 also has the leg portions 5 enlarged at their lower ends as shown at 6 to inclose the shoes 60 of the wearer. The leg portions 5 are divided at their lower portions, as shown at 7, and provided with suitable closure or lacing means 8 whereby the leg portions may be securely fastened around the legs of the 65 wearer from the feet to the knees to make the device comfortable. Suitable tongues 9 are secured to the divided portions of the legs 5 to prevent water from entering the suit at this point. It will also be evident 70 that by constructing the leg portions of the suit in this manner, one size suit may serve for parties of various sizes.

The suit is also provided with an upstanding neck portion 10 adapted to be securely 75 fastened around the neck of the wearer and the front of the suit is open from the top of the upstanding neck portion to about the waist line and provided with suitable closure means such as the fastener shown in the 80 drawings by the numeral 11. The front of the suit is provided with an inner member 12 also divided and provided with a separate fastener 13 and a tongue 14 is secured by its opposite edges to the inner member 12 along 85 the divided portion of the same to prevent water from reaching the wearer of the suit. Between the separable closures 11 and 13 is positioned an inflated chest member 15 having a suitable valve 16 for connection with a 90 pump or the like. The neck of the suit is also provided with an interior inflatable member 17 having a projecting valve 18 similar to the valve 16, whereby the suit may be readily tightened around the neck of the 95 wearer. The entire suit is provided with a lining 19 of any suitable material to protect the wearer of the suit from the effects of the cold water.

Suitable belt supporting straps 20 are secured upon the outer face of the body of the suit to support a life belt 21 around the waist of the wearer, as shown in Fig. 1, the life belt being fastened in the usual manner, as shown at 22.

From the foregoing, it will be readily apparent that this suit may be readily secured upon a party about to enter the water and any party wearing this suit will be able to remain in the water an indefinite number 110 of hours. It will therefore be seen that this suit is especially adapted for use as a life-

saving suit to be carried upon a vessel and used by parties compelled to leave the vessel suddenly. The suit is also adapted for use by life savers, fishermen, duck hunters, etc.

5 While the preferred embodiments of the invention have been shown and described, it will be understood that minor changes in the details of construction, and arrangement of parts may be resorted to within the scope of 10 the appended claims without departing from the spirit of the invention or sacrificing any of the advantages of the same.

What is claimed is:

1. A life saving suit comprising a body portion having integral arm and leg portions terminating respectively in integral gloves and feet covering, each of said leg portions being divided longitudinally and having secured to the edges of said division 20 to prevent the entrance of water thereinto a flexible tongue, lacing means for drawing the edges of said divided portions together, a division extending from the waist line of 25 the suit upwardly to the neck at the front thereof having a flexible tongue on the inner side secured at its edges to the edges of said opening, closure means for said divided por-

tion and inflatable members within the suit at the neck thereof.

2. A life saving suit comprising a body portion, integral arm portions having integral gloves at the extremities thereof, leg portions having enlargements on the ends to receive the feet of the wearer, said suit being divided at the front from waist line upwardly to the neck, closure members on the edges of said division to secure the same together, an inner member secured at its ends to the body portion in rear of the division formed therethrough, said inner member being also vertically divided and having fastening members on the edges thereof, a flexible tongue secured at its edges to the edges of said inner member to prevent the passage of water into said suit, an inflatable member between the front of the suit and the inner member, and an inflatable member encircling the neck of the suit.

In testimony whereof I affix my signature in presence of two witnesses.

CARL B. CHEEK.
